UNITED STATES PATENT OFFICE.

ROBERT S. GROVES, OF PHILADELPHIA, ASSIGNOR TO THE LUKENS IRON
AND STEEL COMPANY, OF COATESVILLE, PENNSYLVANIA.

DESIGN FOR A PAPER-WEIGHT.

SPECIFICATION forming part of Design No. 21,201, dated December 1, 1891.

Application filed October 31, 1891. Serial No. 410,527. Term of patent 3½ years.

To all whom it may concern:

Be it known that I, ROBERT S. GROVES, a citizen of the United States, and a resident of Philadelphia, Pennsylvania, have invented a
5 Design for a Paper-Weight, of which the following is a specification.

My design is fully shown in the accompanying drawings, in which Figure 1 represents a perspective view of the weight, and Fig. 2
10 a plan view of the same.

The design comprises a base-piece A and a top piece B. Both the base-piece and the top piece have squared ends *a*; but said base-piece has recessed sides *b*, the recesses being
15 straight or substantially straight with rounded ends. The top piece also has recessed sides *d*, said recesses being longer and deeper

than those in the base-piece, so that the base projects laterally beyond the top piece in the recessed portions. The sides of the recessed 20 portion of the top piece converge from the ends toward the point *f*, where there is a transverse fracture in said top piece.

I claim—

The design for a paper-weight, substantially as described, and as shown in the accompanying drawings.

In testimony whereof I have signed my name to this specification in the presence of two subscribing witnesses.

ROBERT S. GROVES.

Witnesses:

EUGENE ELTERICH,
HARRY SMITH.
